UNITED STATES PATENT OFFICE.

STELLA A. GILL, OF CHATHAM, MASSACHUSETTS.

DESIGN FOR A TOY WINDMILL.

61,185.

Specification for Design.

Patented July 4, 1922.

Application filed November 30, 1921. Serial No. 519,005. Term of patent 7 years.

To all whom it may concern:

Be it known that I, STELLA A. GILL, a citizen of the United States, residing at Chatham, in the county of Barnstable and State of Massachusetts, have invented a new, original, and ornamental Design for a Toy Windmill, of which the following is a specification, reference being had to the accompanying drawing, forming part thereof.

The figure is a perspective view of a toy windmill showing my new design.

I claim.

The ornamental design for a toy windmill, as shown.

STELLA A. GILL.
